Primary Examiner — Jae Liang(57) **CLAIM**

The ornamental design for a beverage container, as shown and described.

DESCRIPTION

FIG. 1 is a front, top perspective view of a beverage container showing our new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The dash-dash broken lines throughout the drawing figures depict portions of the beverage container that form no part of the claimed design. The broken lines and unshaded surfaces bounded by broken lines form no part of the claimed design.
